CLAIM

The ornamental design for an industrial endoscopic observation device, as shown and described.

DESCRIPTION

FIG. 1 is a front, top and left side perspective view of an industrial endoscopic observation device showing my new design;

FIG. 2 is a front, top and left side perspective view where the monitor shown in an opened position thereof;

FIG. 3 is a front, top and right side perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a right side elevational view thereof; and,

FIG. 9 is a left side elevational view thereof.

The present article is an industrial endoscopic observation device which has a monitor for observing and an operation panel and in which requisite electric circuits and battery are stored.
